UNITED STATES PATENT OFFICE

JOZSEF BEREZ, OF BRIDGEPORT, CONNECTICUT.

FLYING AND SPINNING TOY.

1,110,738.

Specification of Letters Patent.

Patented Sept. 15, 1914.

Application filed March 25, 1914. Serial No. 327,160.

To all whom it may concern:

Be it known that I, JOZSEF BEREZ, a subject of the King of Hungary, residing at Bridgeport, in the county of Fairfield and 5 State of Connecticut, have invented certain new and useful Improvements in Flying and Spinning Toys, of which the following is a specification.

This invention relates to certain new and 10 useful improvements in flying and spinning toys.

The primary object of the device is to provide an aerial toy adapted for an initial flying movement imparted thereto by reason of 15 its own revolutions and its course being completed in spinning as a top upon a fixed surface.

A further object of the device is to provide a spinning top with an aerial propeller 20 and whereby the top first spins in a flying movement through the air and later continues its spinning upon the ground when the same is reached during its travel.

A still further object is to provide an extremely light spinning top with a flying propelling means and a means for spinning the propeller and top for a combined flying and 25 spinning top operation.

With these general objects in view and 30 others that will appear as the nature of the invention is better understood, the same consists in the novel combination and arrangement of parts hereinafter fully described, illustrated in the accompanying 35 drawings, and pointed out in the appended claims.

In the drawings forming a part of this application and in which like designating characters refer to corresponding parts 40 throughout the several views; Figure 1 is a side elevation of the device about to be actuated, the hands of the operator being shown in dotted lines, and, Fig. 2 is a vertical longitudinal sectional view taken through the shaft thereof and portions of the device being broken away.

Referring more in detail to the drawings, it will be noted that the main elements of the toy consist of the rigid shaft 10 having 45 a double propeller blade 11 rigidly secured

to one end thereof while its opposite end is provided with a hollow spherical body or two-part top 12, the latter being secured upon said shaft and terminating in a spinning point 13 in alignment with the direction of the shaft 10, and at a diametrically opposite point upon the spherical top 12. 55

The shaft is provided at its substantially central point with an integral stop 14 for the reception of a cord 15 adapted to be wound thereon but unsecured thereto while between the top 12 and said spool a split sleeve 16 is positioned and longitudinally through which the shaft 10 is journaled.

From this detailed description of the device, the complete operation thereof is believed to be apparent in that, the cord 15 being wound upon the spool 14 as illustrated in Fig. 1, the shaft and propeller are rapidly revolved by pulling outwardly upon the free end of the cord while the sleeve 16 is firmly held in the other hand of the operator, all as illustrated in said figure. Such a forcible revolving of the propeller blade 11 imparts an upward impulse to the entire 70 device and which upon being released by the operator flies upwardly until its lifting power is gradually exhausted and the structure falls to the ground and its continued revolutions carry the same in a spinning 75 movement upon the point 13 of the top and which spinning of the top terminates with the ceasing of the shaft to further revolve. 80

While the forms of the invention herein shown and described are what are believed 85 to be preferable embodiments thereof, it is nevertheless to be understood that various forms and modifications thereof may be had without departing from the spirit and scope of the invention as claimed. 90

What I claim as new and desire to secure by Letters Patent is—

1. A toy comprising a shaft, an elevating propeller at one end and a hollow top at the other end thereof, a spool positioned substantially centrally of the shaft, a winding cord mounted upon said spool and a freely revoluble split sleeve journaled upon said shaft between said spool and top. 95

2. A device of the class described compris- 100

ing a hollow spherical top, a spinning point and a shaft secured in alinement with each other extending from diametrically opposite points upon said top, a propeller 5 blade secured to the free end of said shaft, an integral central spool upon said shaft, a split sleeve journaled between said spool and top, and a cord wound upon said spool and

adapted for unwinding simultaneously with the revolving of said shaft.

In testimony whereof I affix my signature in presence of two witnesses.

JOZSEF BEREZ.

Witnesses:

GEORGE PHILLIPS,
MORRIS SZOLLOSY.
